UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

LAY ROCKER-SHAFT BEARING FOR LOOMS.

Application filed January 16, 1924. Serial No. 686,520.

To all whom it may concern:

Be it known that I, ALONZO E. RHOADES, a citizen of the United States, residing at Hopedale, in the county of Worcester and State of Massachusetts, have invented an Improvement in Lay Rocker-Shaft Bearings for Looms, of which the following description in connection with the accompanying drawings is a specification, like characters on the drawings representing like parts.

This invention relates to lay rocker-shaft bearing for looms suspended from the side frames of the loom.

The lay rocker-shaft, in looms of the ordinary type, supports the weight of the lay, the lay swords, the shuttle boxes and other parts, and its constantly oscillating motion during weaving causes the lay rocker shaft bearings to wear rapidly with the result that the lost motion thereby effected lowers the lay and interferes with the proper weaving operation.

One of the objects of the present invention, therefore, is to provide a lay rocker-shaft bearing of anti-friction type which primarily supports the entire weight of the lay rocker-shaft and its load and may be readily adjusted in an upward and downward direction to maintain the parts in proper operative position. In accordance with the present invention, the anti-friction bearing for supporting the weight of the lay rocker-shaft and its load is formed as a frame adjustably connected to the side frame of the loom and adjustable in an upward direction to maintain the lay rocker-shaft and anti-friction devices in proper supporting position regardless of wear. The suspension frame for the anti-friction devices, preferably formed as rollers, consists of sustaining leg portions between which is an anti-friction roller supporting cage disposed below the lay rocker-shaft, and in order to relieve the lay rocker-shaft itself from any wear due to its oscillating motion, the present invention contemplates providing the lay rocker-shaft with a collar having a flange portion below the lay rocker-shaft to rest upon the anti-friction devices.

The various features of novelty and new combination of parts will best be made clear from the following description and the accompanying drawings of one good form of

the invention, the scope of which will be definitely defined by the claims.

In the drawings:

Fig. 1 is a perspective view of one side of the loom at the lower portion thereof, showing one end portion of the lay rocker shaft as provided with the present invention;

Fig. 2 is a side elevation of the lay rocker shaft bearing viewed from the inside of the loom frame, the lay rocker-shaft itself being shown in section; and

Fig. 3 is a section on the line 3—3 of Fig. 2.

The loom is provided as usual with two side frames 1, one at each side of the loom, between which extends the lay rocker-shaft 2, and as usual the lay rocker-shaft extends through the side frames and its outer portion has secured thereto a shoe for the picker motion. Secured to and extending upwardly from the lay rocker-shaft are the lay swords 3, one of which only is shown, it being understood that the opposite side of the lay rocker-shaft has another lay sword secured thereto.

Each of the side frames 1 of the loom has an opening 4 through which the lay rocker-shaft 2 extends, and in the present instance the loom frame has secured to the outer side thereof the main bearing or bushing member 5, the bushing 6 of which extends inwardly through the opening 4 of the adjacent side frame. The main bearing or bushing member 5 is secured to the loom frame by suitable bolts 7 which pass through the openings 8, enlarged laterally to permit the bearing or bushing member 5 to be adjusted towards and from the front of the loom. On the outwardly extending portion of the lay rocker-shaft 2 at each side of the loom is secured a shoe member 9 having the bearing portion 10 for the rocker 11 of the picking motion, which may be of usual character, and being well known needs no further description.

Secured to the adjacent side frame of the loom is an anti-friction bearing suspension frame, shown in the present instance, as comprising the two leg portions 12 between which extends the roller bearing cage 13 in which rest the rollers 14 or like anti-friction devices. The rollers 14, as shown, are held in the cage 13 by the side projecting

portions 15 of the roller cage. At their upper portions the legs 12 of the suspension frame are turned, as at 16, to overlie the flange portion 17 of the adjacent side frame, 5 and each is provided with an opening through which extends an adjusting screw 18, the lower end of which rests upon the flange 17 of the adjacent side frame, the construction being such that by manipulation 10 of the adjusting screws 18 the suspension frame 12 and the roller cage below the lay rocker-shaft may be adjusted in a substantially vertical direction. As shown, each of the adjusting screws 18 is provided 15 with a lock nut 19 whereby when the suspension frame has been properly adjusted the parts may be locked in the adjusted position.

Between the leg portions 12 of the suspension frame and the roller cage 13 the suspension frame has side extending portions 20, Fig. 2, each of which is provided with the vertically extending openings 21 through which project the screws or bolts 25 7, hereinbefore described as securing the bearing or bushing 5 in its laterally adjusted position.

Between the lay swords 3 and the adjacent side frame of the loom, the lay rocker-shaft 30 is provided with a collar 22 which may be secured thereto in fixed position by the headless set screws 23. The collar 22 is provided on its under portion with a widened flange 24 which rests upon the rollers in the underlying roller cage 13 and such flange preferably extends over the rollers to exclude therefrom lint, dirt and other foreign substances.

As shown in the present instance of the 40 invention, the collar 22 is secured to the lay rocker-shaft between the adjacent lay sword 3 and the end of the bushing or bearing 6 through which the lay rocker-shaft extends, the construction being such that the parts 45 are associated in fixed and unvarying position.

The cage 13 as shown is preferably formed as a segment or part of an annulus, and similarly the flange 24 of the collar 22 is 50 formed as a segment which provides an enlarged surface bearing resting upon the anti-friction rollers 24.

In the present embodiment of the invention the suspension frame is shown as on 55 the inside of the adjacent loom side frame, while the bearing member or bushing 5 is on the outside of the same loom side frame, and while this is preferred, the invention is not necessarily limited to this disposition 60 of the parts which of course might be reversed within the true scope of the invention.

From the construction described it will be 65 obvious that the bearing member 5 and bushing 6, which as hereinbefore described, may

be adjusted laterally and also vertically by reason of the slots in the main side frame, serve to laterally position the rocker-shaft bearing 2 in the side frames, or define its position towards and from the front of the 70 loom, while the suspension frame and the anti-friction devices support the entire weight of the lay rocker-shaft and its load, so that by the simple adjustment of the suspension frame all wear may be readily taken 75 up and the lay rocker-shaft, lay and other parts be maintained in their proper operative position. From the construction described it will be apparent that the roller bearing being positioned below the lay 80 rocker-shaft and adjustably connected to the adjacent side frame independent of the bearing or bushing member 5, vertical adjustment of the lay rocker-shaft may be readily accomplished to maintain the lay 85 and other parts in proper operative position, and if desired the roller cage 13 may be entirely removed from the loom and another substituted in its place without necessitating the removal of the lay shaft or associated parts.

What is claimed is:

1. In a lay rocker-shaft bearing for looms, the combination of the side frames of the loom, each having a bearing for adjustably positioning the rocker-shaft towards and from the front of the loom, and an independent anti-friction bearing upon each side frame for supporting the weight of said shaft, consisting of an open arcuate cage 95 carrying anti-friction devices and applicable to the lay rocker-shaft while the latter and parts carried thereby are in operative position, and means for adjusting the cage to 100 compensate for wear.

2. In a lay rocker-shaft bearing for looms, the combination of the side frames of the loom each having a main bearing for the rocker-shaft which is adjustable towards and from the front of the loom, an independent anti-friction bearing constructed and arranged to be applied to the lay rocker-shaft while the latter is supported in the main bearings in undisturbed operative position, and means for adjustably supporting 110 the anti-friction bearing from the loom frame that it may be adjusted with or independently of the main bearing.

3. In a lay rocker-shaft bearing for looms, the combination of the side frames 120 of the loom each having a main bearing for the rocker-shaft which is adjustable towards and from the front of the loom, an independent anti-friction bearing constructed and arranged to be applied to the lay 125 rocker-shaft while the latter is supported in the main bearings in undisturbed operative position, and means for adjusting the anti-friction bearing relative to the main bearing to compensate for wear.

4. In a lay rocker-shaft bearing for looms, the combination of the lay rocker-shaft, a main bearing at each side of the loom for the lay rocker-shaft, an independent anti-friction bearing for supporting the weight of the lay rocker-shaft constructed and arranged to be applied to the lay rocker-shaft while the latter is supported in the main bearings in undisturbed operative position, means for vertically adjusting the anti-friction bearings relative to the main bearings, and bolts for securing the main bearings and anti-friction bearings to the main frame in their relatively adjusted positions. 65
5. In a lay rocker-shaft bearing for looms, the combination of the side frames of the loom, the lay rocker-shaft extending between the side frames, a main adjustable bearing for determining the position of the lay rocker-shaft in a direction towards and from the front of the loom, an anti-friction bearing frame having a cage for supporting anti-friction rollers below the lay rocker-shaft, a collar secured to the lay rocker-shaft and having a shoe at the underside thereof which rests upon the anti-friction rollers and supports the weight of the lay rocker-shaft, means for adjusting the anti-friction bearing suspension frame on the loom frame in a direction to maintain the rollers and shoe in rocker-shaft weight supporting position and means for securing the main bearing and friction bearing to the loom frame in fixed adjusted positions. 70
6. In a lay rocker-shaft bearing for looms, the combination of the loom frame, a lay rocker-shaft, a main bearing for the rocker-shaft, and an anti-friction bearing for the rocker-shaft comprising side members having an open cage between them permitting the anti-friction bearing to be placed about the lay rocker-shaft while in lay supporting position, anti-friction devices carried in the open cage, a shoe on the rocker-shaft to rest upon the anti-friction devices, and means for adjusting the open cage in a vertical direction. 75
7. In a lay rocker-shaft bearing for looms, the combination of the side frames of the loom, the lay rocker-shaft between the side frames, lay swords secured to the lay rocker-shaft, a suspension frame having leg portions adjustably secured to the loom frame, an open roller bearing cage extending between the leg portions of the suspension frame below the lay rocker-shaft, a collar secured to the lay rocker-shaft between one of the lay swords and adjacent side frame of the loom, and a flange carried by the collar and resting upon the rollers below the lay rocker-shaft. 80
8. In a lay rocker-shaft bearing for looms, the combination of the side frames of the loom, each having a bearing for positioning the rocker-shaft, and an independent anti-friction bearing upon each side frame for supporting the weight of said shaft, consisting of an open cage that embraces only the lower portion of the lay rocker-shaft constructed and arranged to be applied to the lay rocker-shaft while in lay supporting position, and anti-friction devices mounted in the cage to support said shaft. 85
9. In a lay rocker-shaft bearing for looms, the combination of the side frames of the loom, each having a main bearing for adjustably positioning the rocker-shaft, an independent anti-friction bearing upon each side frame near the first-mentioned bearing and adapted to support the weight of the lay rocker-shaft to relieve the first-mentioned bearing from wear, means for adjusting the anti-friction bearing in an upward direction relative to the main bearing to compensate for wear and bolts for securing the main bearing, the anti-friction bearing and side frame to the loom in their relatively adjusted positions. 90
10. In a lay rocker-shaft bearing for looms, the combination of the lay rocker-shaft, a main bearing for the rocker-shaft adjustable towards and from the front of the loom, an anti-friction bearing frame comprising two suspension members, an open arcuate cage extending between said members constructed and arranged for application to the lay rocker-shaft laterally thereof while in lay supporting position, an adjusting screw for each of said suspension members, and anti-friction devices supported in the open arcuate cage for sustaining the weight of the lay rocker-shaft. 95
11. In a lay rocker-shaft bearing for looms, the combination of the lay rocker-shaft, a main bearing for the rocker-shaft adjustable towards and from the front of the loom, an anti-friction bearing frame comprising two suspension members, an open arcuate cage extending between said members constructed and arranged for application to the lay rocker-shaft laterally thereof while in lay supporting position and projecting from the suspension members lengthwise of the lay rocker-shaft, flanges at the sides of the open arcuate cage, anti-friction devices between said flanges, and means for adjusting the open arcuate cage vertically. 105
- In testimony whereof, I have signed my name to this specification. 110
